UNITED STATES PATENT OFFICE.

LEONARD D. MORRIS, OF CHICAGO, ILLINOIS.

CHIME-MOUNTING.

1,361,084.

Specification of Letters Patent. Patented Dec. 7, 1920.

Application filed August 7, 1919. Serial No. 315,802.

To all whom it may concern:

Be it known that I, LEONARD D. MORRIS, a citizen of the United States, residing at Chicago, in the county of Cook and State 5 of Illinois, have invented certain new and useful Improvements in Chime-Mountings, of which the following is a specification.

My invention relates to chime mountings and has for its primary object the provision 10 of improved means for suspending chimes so as to permit the freest possible vibration thereof. Another object is to provide novel means for tightening the cord on which a chime is hung, thus keeping the cord taut 15 regardless of the slight stretching which may occur in it. A further object lies in the provision of an extremely cheap and readily assembled type of chime mounting; and a still further object is the provision 20 of a single piece frame plate adaptable to the mounting of chimes of various sizes and to the proper guiding of dampers for the mounted chimes.

Other objects and advantages of the invention will appear from the following description, taken in conjunction with the accompanying drawings which form a part of this specification and illustrate the preferred embodiment of the invention.

30 In the drawings:

Figure 1 is a front elevation of the invention as adapted to the mounting of three chimes, all of which have their lower portions broken away and one of which is axially sectioned.

Fig. 2 is a section taken on line 2—2 of Fig. 1.

Fig. 3 is a view in perspective of the frame plate of the present invention, showing certain cord holding pins and buttons in place thereon.

Fig. 4 is a perspective view of one of the cord-holding pins of the invention taken from the rear of the pin.

45 This invention is shown but not claimed in my co-pending application, Serial No. 315,801, filed August 7, 1919.

The main support for the present invention comprises a horizontal wooden bar 10 against the forward vertical face 11 of which is screwed a frame plate 12. This plate comprises a piece of sheet metal punched to form depending arms 13 which are of such length and so spaced from each 55 other as to accommodate between adjacent arms any ordinary size and type of chime.

A cord holding button 14 is fixedly mounted on the lower end of each arm 13 and projects forwardly therefrom, each button being formed with a peripheral cord receiving groove 15. The buttons 14 are horizontally alined so that chime hanging cords may be stretched horizontally between them.

Above the arms 13 a horizontally alined series of pin receiving holes 16 is provided in plate 12, each preferably slightly tapered from front to back of the plate. These holes are arranged so that one pair of spaced holes 16 stands above the space between each pair of adjacent arms 13. A cord stretching pin is provided for each hole 16, these pins each comprising a screw shank 17 frictionally held in its plate hole 16, and a round head 18 eccentrically fixed on the shank and having a peripheral cord receiving groove 19.

For convenience three chimes, 21, 22 and 23, are shown in Fig. 3. Each of these is suspended by means of an endless cord 24, preferably of rawhide, which is slipped over two adjacent buttons 14 and the pair 80 of pins 18 above and between those buttons. When slipping the cords over the pins the latter are rotated—by means of screw-driver slots 25 formed in their heads—to turn the greatest possible portion of the head of each 85 inwardly of the four sided figure formed by the cord; this position of the pins being shown above chimes 21 and 22. One advantage in the use of rawhide cords, in this invention, lies in the fact that such cords 90 will elongate when wetted and may be made of such length that they will just slip over the buttons and inturned pins when in that condition. Upon drying the rawhide cords will shrink longitudinally, thus drawing 95 each one so tightly over the buttons and inturned pins as to leave its lower, chime carrying reach 26 substantially horizontal and only very slightly bent downward under the weight of its chime. This latter condition 100 of a rawhide cord is shown in the assembly of parts which supports chime 21 in Fig. 1. However, after sustaining the weight of a chime for some time, a new, dried cord may elongate slightly, causing the weight 105 of the chime—as in the cord supporting chime 22 in Fig. 1—to bend the lower reach 26 far down. This greatly downbent condition of the cord tends to interfere with the vibration of the chime, the freest vibration 110 thereof occurring in a truly horizontal condition of the chime supporting portion of

the cord. To correct the looseness resulting from such elongation of a cord, one or both of the pair of pins 18 are turned outwardly as in the assembly of parts supporting chime 23, to interpose a larger portion of each head 18 between the cord and the axis of shank 17 of the pin, thus elongating the grooved path over which the cord must pass. stretching the cord, and again drawing its 5 lower reach 26 back to a substantially horizontal condition. The frictional engagement between shanks 17, wood 10 and the walls of plate holes 16 serves to hold the pin heads 18 in this outturned position against 10 the weight and vibration of the chime.

The grooves 15 of buttons 14 are of sufficient width to accommodate two thicknesses of cord 24, it being an advantage of this invention that, except for the extreme 20 end buttons, each button 14 carries and holds two adjacent cords 24, this arrangement reducing to a minimum the number of buttons required. At 27 in chime 21 of Fig. 1 is shown, in section, the cord receiving tube, normally provided in modern chimes, axially traversing the chime near 25 its upper, closed end.

In the above mentioned, co-pending application, I have shown for each chime a 30 chime damper carried on a vertical damper rod vertically movable to and from the top of the chime. It is a further advantage of the present invention that, when punching out frame plate 12, it may be formed on 35 its lower edge midway between adjacent arms with a forwardly projecting tongue 28, vertically apertured above the top of the chime to form a bearing for the damper rod.

I claim:

40 1. In a chime mounting, the combination with a suitable frame, of a plurality of spaced cord holding members and a chime supporting cord passing about said members, one of the members being adjustable to 45 take up slack in said cord.

2. In a chime mounting the combination with a suitable frame, of a plurality of spaced cord holding members, two of said members being horizontally alined, and a 50 chime supporting cord passing about said members, one of the members being adjustable to take up slack in said cord.

3. In a chime mounting, the combination with a suitable frame, of a pair of spaced, 55 horizontally alined cord holding buttons fixedly mounted therein, a pair of rotatively adjustable shanks frictionally wedged into the frame, a cord holding head eccentrically mounted on each shank, and an endless cord stretched over said buttons and heads.

4. In a chime mounting, the combination with a frame comprising spaced depending arms, of a series of cord holding buttons fixed one on the lower end of each arm and 65 horizontally alined, there being a pair of

pins receiving holes provided in the frame above each pair of adjacent buttons; a pin for each of said holes comprising a cord holding head, and an eccentrically projecting shank for frictional engagement with 70 the wall of one of the holes, and an endless cord fitting tightly about each adjacent pair of buttons and their superposed pair of pins.

5. In a chime mounting, the combination 75 with a frame comprising a series of spaced depending arms, of a series of cord holding buttons fixed one on the lower end of each arm and horizontally alined, a pair of cord holding pins mounted in the frame above 80 each pair of adjacent buttons, in a common plane with the buttons, and each adjustable eccentrically about an axis angled with respect to said common plane, and an endless chime supporting cord fitting about each set 85 of two buttons and two pins.

6. In a chime mounting, the combination 90 with a frame comprising a series of spaced depending arms, of a series of cord holding buttons fixed one on the lower end of each arm and horizontally alined, a pair of cord holding pins mounted in the frame above 95 each pair of adjacent buttons, in a common plane with the buttons, and each adjustable eccentrically about an axis angled with respect to said common plane, and an endless chime supporting cord fitting about each set of two buttons and two pins; certain of said buttons holding overlapped portions of adjacent cords.

7. In a chime mounting, the combination 100 with a frame comprising a pair of spaced arms, of a pair of cord holding buttons fixed one on the end of each arm, cord holding means mounted in the frame remote from 105 said buttons, and an endless chime supporting cord fitting about said buttons and means; said means being adjustable to take up slack in the cord.

8. In a chime mounting, the combination 110 with a frame comprising a pair of spaced arms, of a pair of cord holding buttons fixed one on the end of each arm, cord holding means mounted in the frame remote from 115 said buttons and comprising a head adjustable toward and from the buttons, said means and buttons being formed with peripheral cord receiving grooves, and an endless chime supporting cord of rawhide fitting in the grooves of said means and buttons.

9. In a chime mounting, the combination 125 with a frame comprising a pair of spaced arms, of a pair of cord holding buttons fixed one on the end of each arm, cord holding means mounted in the frame remote from 125 said buttons and comprising a head adjustable toward and from the buttons, and an endless chime supporting cord fitting about said means and buttons and formed of a 130

material which elongates when wetted and contracts longitudinally when dried.

10. A chime mounting comprising a flat sheet of metal horizontally elongated, spaced 5 parallel arms extending from one longitudinal edge thereof, a cord holding button on each arm, and a chime supporting cord engaged with adjacent buttons.

11. As an article of manufacture a chime 10 mounting frame, comprising a flat sheet of metal having one of its edges mutilated to form a series of spaced parallel coextensive arms and a metal tongue between each pair of adjacent arms.

15. 12. As an article of manufacture, a chime mounting frame comprising a sheet of

metal, provided with spaced chime supporting arms extending from a common edge thereof and formed to resist strains exerted in the plane of said sheet of metal and cross- 20 wise of said arms, and a cord holding button mounted on each of said arms.

13. In a chime mounting, the combination with a frame comprising a horizontally elongated sheet of metal, and a series of 25 spaced arms projecting from one edge thereof; of a cord holding button fixed on each arm, and cord holding and tightening means mounted in the plate near each pair of adjacent buttons.

LEONARD D. MORRIS.
